UNITED STATES PATENT OFFICE.

HERBERT A. CHURCH, OF CRARY MILLS, NEW YORK.

GAS VAPORIZER.

Application filed August 11, 1920, Serial No. 402,880. Renewed June 8, 1923.

To all whom it may concern:

Be it known that I, HERBERT A. CHURCH, a citizen of the United States, residing at Crary Mills, in the county of St. Lawrence and State of New York, have invented certain new and useful Improvements in Gas Vaporizers, of which the following is a specification.

This invention relates to improvements in fuel atomizers, designed for use in connection with internal combustion engines, and has for its object to provide novel and simple means for reatomizing the explosive mixture after it has passed from the carburetor towards the engine cylinders.

At the present time, the explosive gas which effects the driving of automobiles, and the like, is drawn by the suction of the pistons from the carburetors, usually through needle-valves, which atomize the gasolene, and the latter is mixed with air in varying proportions before it reaches the compression chambers of the engines. This explosive mixture is usually carried to the cylinders through a common intake manifold, which is arranged to supply the cylinders individually. The distance the mixture has to travel from the ordinary mixing chamber, near the carburetor, to the several cylinders varies greatly, and it has been found that during this passage there is a tendency for the gas to become more or less condensed before it is finally exploded. This is especially true of the more remote cylinders, which accordingly receive the vapor in a coarser state than the nearer cylinders, and therefore yield correspondingly less power. Furthermore, owing to the fact of this imperfect vaporization of the explosive element, a considerable portion of the gasolene passes through the engine unconsumed.

A particular object of the present invention is primarily to save gasolene and therefore get more car mileage from each gallon of gasolene, by providing means for re-vaporizing the explosive mixture. This is accomplished by disposing a number of similar adjustable atomizing members in the several passages through which the gas flows from the usual mixing chamber to the engine cylinders. In the preferred arrangement, these auxiliary atomizers are disposed

at or near the junction of the intake manifold with the several cylinders. 55

I attain these objects by the means set forth in the detailed description which follows, and as illustrated by the accompanying drawing, in which—

Figure 1 is a side view of a gas engine to which my improvement is applied. Fig. 2 is a central vertical longitudinal section through the intake manifold. Fig. 3 is a vertical cross-section, taken on line 3—3 of Fig. 1. Fig. 4 is respectively an edge and a face view of the adjustable wing carried by each spherical body. Fig. 5 is a modification of the means for holding the balls in place. 60 65

In the drawing, 2 represents conventionally a gas engine. 3 is the carburetor, and 4 is the usual intake manifold, which conducts the explosive mixture from the carburetor to the engine cylinders, the two discharge arms of the manifold being indicated at 4' and 4^a. My improved atomizers preferably consist of similar spheres or balls 5, which may be made of any suitable metal. For the ordinary manifold 4, I prefer to employ two or more of the spheres 5, one being preferably disposed in the open end of each of the arms 4' and 4^a, at the nearest point to the cylinders 2', as best seen in Figs. 2 and 3. The balls 5 are perforated diametrically and are preferably threaded to receive the threaded portions of bolts 6, which pass through the arms of the manifold, the latter being threaded at one side to hold the bolts in place. By this construction and arrangement, the balls 5 may be adjusted and set in different positions relatively to the bore of the arms 4' and 4^a, as shown by the full and dotted lines in Fig. 2. The balls 5 may be of any suitable diameter, but they are preferably large 70 75 80 85

enough to partially close or choke the passages leading from the manifold to the cylinders, so that the gas may be drawn past the balls with sufficient force to effectually atomize or break it up before it enters the compression chambers. In order to further atomize as well as to direct the flow of the gas towards one or the other side of each passage, I provide an adjustable wing 7, which is preferably pivotally attached to 90 95 100 105 each of the balls 5, by screws 7', the said

wings preferably being disposed on the side nearest the cylinders and being movable laterally to the extent shown in Fig. 4.

5' represents a plain sphere, which is mounted upon a threaded rod 8, the latter being adjustably supported by a screw-plug 9, which is preferably received in a threaded opening 9', the latter being located about midway between the arms 4' and 4^a, and substantially in line axially with the vertical portion 4^b of the manifold (see Fig. 2). The ball 5' is preferably suspended in the hollow neck 4^b, as shown, and tends to re-atomize the gas before it enters the arms 4' and 4^a. In order to further aid in breaking up the gas in the leg 4^b, I sometimes insert in this funnel-shaped portion a loose roll of woven-wire 10, as shown in Fig. 2.

The modification shown in Fig. 5 consists of applying to the spheres 5^a a plurality of radial wire legs 11, preferably made of spring metal, which may be bent when applying the ball to a gas passage, and whose tension tends to hold the ball in place, as shown. The legs 11 are preferably provided with serpentine feet, for increasing the frictional contacts of the parts.

Having thus described my invention, what I claim as new and desire to secure by Letters Patent, is—

1. In reatomizers, the combination with the cylinders of an internal combustion engine and an intake manifold, of a plurality of spherical members disposed in the gas passages of the manifold, means for adjusting said members, and a wing pivotally supported by each member adapted for diverting the gas towards the opposite sides of said passages.

2. The combination with the cylinders of a gas engine and the intake manifold connected thereto, of a plurality of stationary spherical members mounted in the gas passages of the manifold, two of said members disposed close to the intake port of the cylinders, the third member being disposed in the down-leg of the manifold adjacent the juncture of the said leg with the arms of the manifold, the members adjacent the intake ports being adjustable for diverting the explosive mixture towards the opposite sides of the intake ports.

In testimony whereof I affix my signature.
HERBERT A. CHURCH.
